CIRCULAR ARROW QUIVER

Floyd B. Reese, P.O. Box 582, Dorris, Calif.

Filed Feb. 24, 1959, Ser. No. 795,158

3 Claims. (Cl. 224—1)

The present invention relates to quivers and has for an object a quiver construction which adapts it for connection with the bow without upsetting the balance of the bow or interfering with the casting of an arrow—in fact, the weight of the quiver and its arrows acts as a stabilizer in lessening the movement of the bow while attempting hold on a target.

A further object is the provision of a quiver so constructed and arranged that the Bowman may move through brush, walk, crawl, stalk, or move under low hanging limbs without the arrows in the quiver, or the quiver itself hanging on brush or catching on limbs.

A further object is the provision of a quiver adapted to be secured to the bow, which holds the arrows securely within the quiver, yet at the same time permits arrows to be withdrawn from the quiver with a minimum of effort, and wherein the quiver does not interfere with the arrows when casting an arrow by the bow.

A further object is the provision of a quiver from which the arrows are easily removed and at speed when it is desired to quickly cast several arrows.

The quiver is so constructed that little noise or no noise at all emanates by reason of the quiver passing through brush.

A further object is the provision of a quiver which may be attached to the bow without interfering with the stringing of the bow.

A further object is the provision of a quiver that, when secured to the bow, will carry enough arrows for a day's hunt without the Bowman having to carry extra arrows.

A further object is the provision of a quiver adapted to carry both hunting arrows as well as target arrows in such a manner as to render all of said arrows easily accessible.

A further object is the provision of a quiver which is inexpensive in cost of manufacture, attractive in appearance and generally superior to quivers now known to the inventor.

With the above mentioned and other objects in view, the invention consists in the novel and useful provision, formation, construction, association and relative arrangement of parts, members and features, all as shown in one embodiment in the accompanying drawings, described generally, and more particularly pointed out in the claims.

In the drawings:

Figure 1 is a perspective view of a bow incorporating the quiver of the invention;

Figure 2 is a fragmentary elevation partly in section, taken substantially on line 2—2 of Figure 1 and enlarged to show details of construction;

Figure 3 is a plan view of one of the rack members used in the quiver, the shafts of arrows in said rack being shown in section;

Figure 4 is a fragmentary sectional detail on an enlarged scale and taken on the line 4—4 of Figure 3;

Figure 5 is a fragmentary sectional detail, on an enlarged scale taken on the line 5—5 of Figure 3;

2

Figure 6 is a fragmentary, partially sectional plan view of a shield adapted to be spaced above the uppermost rack, as shown in Figures 1 and 2;

Figure 7 is a fragmentary, partially sectional view, looking in the direction of arrow 7, in Figure 6; and,

Figure 8 is a perspective view of a modified form of shield adapted to spacedly overlie the uppermost rack.

Referring now to the drawing and specifically to Figure 1, I have provided a bow 1 having upper and lower

limbs 2 and 3 respectively, with a hand grip 4 to which limbs between the nock portions thereof is secured the bow string 5. It is obvious that the bow may assume various configurations, but usually in this art the bow limbs have a half round face and a flat surfaced back.

15 As stated, I do not contemplate any particular type of bow, nor for that matter, any particular type of arrows as the circular arrow quiver of the present invention is adapted for all types of arrows and bows. The circular arrow quiver includes an upper rack 6 and a lower rack

20 7. Each rack is of substantially identical construction and these racks are adapted to be secured to the upper and lower limbs of the bow in substantial parallelism and alignment. I have found from experience that circular or round racks are capable of performing desirable functions in my type of quiver. Describing the rack shown in Figure 3, the said rack is a laminated structure and

25 preferably formed from a combination of leather and plastic or for that matter, from rubber or other material and in the present instance, as shown in Figure 4, the rack

30 is laminated, having an intermediate leather member 8 and two outer members 9 and 10 which may be plastic or rubber to give stiffness thereto and likewise add to its ornamental appearance. The laminations are glued or otherwise secured together and the laminations are so

35 formed as to provide spaced apart outwardly opening slots 11 of which there may be a multiple number depending upon the rack diameter and which slots have constricted throats at 12 so as to have pinch engagement with the shafts of the arrows as hereinafter described.

40 In addition to the slots 11 which are adapted to confine therein hunting arrows, I have provided a series of spaced apart openings such as shown at 13, concentrically arranged relative to the center of said rack and inward from the slots 11 which may confine target arrows. In

45 this instance, each opening or aperture 13 has equidistantly spaced apart radial cuts 14 opening into the aperture and the aperture is preferably of smaller diameter than the diameter of the practice arrow shaft so that when the shaft is passed inwardly of said aperture, the

50 segmental portions between the radial cuts 14 are bent upwardly and frictionally engage the shaft to hold the same. To secure the rack to a bow limb, either the upper or lower limb, the construction shown in Figures

55 2 and 4 is utilized and wherein the outer laminations 9 and 10 are bent at right angles as shown in Figure 2 to provide portions 15 and 16. Leather sleeves 17 and 18 in part surround the bow limb and straps or thongs 19 and 20 encircle the portions 15 and 16 and the sleeves 17 and 18. The straps 19 and 20 are tied or otherwise

60 secured by means, such as buckles 21, to cause tight engagement of said members with the bow and thereby prevent relative slippage therebetween. Referring to Figure 3, the rack is provided with a radial slot 22, which slot receives a bow limb. The leather sleeves 17 and 18

65 surround the faces of the bow and one side edge 23 thereof leaving an opening slot for entrance of the bow at 24. Both racks are similarly constructed and each rack is provided with an axial bore as shown at 25 and

70 26 in Figure 2. An elongated tie rod 27 extends between the upper and lower racks, the said tie rod being screw threaded inward from each end as shown at 28 and 29 with the tie rod passed through the bores 25 and

26, the tie rod at the threaded zones carrying pairs of washers and nuts which engage the upper and lower surfaces of each rack and hold the racks so that they are stably positioned on the bow limbs.

Above the upper rack 6, I provide a shield 30 which may be of the form shown in Figures 6 and 7 or of the form shown in Figure 8. That form of shield shown in Figures 6 and 7 has a semi-circular portion 31 of the same radius as the radius for one of the racks and with convergent sides 32 and 33 diametrically connecting said semi-circular portion. The shield is slotted radially inwardly at 34 between the convergent sides 32 and 33 with the spacing between sides of the slot generally increasing in width inwardly of the shield. Depending from the convergent sides are skirting or flanges 35 and 36. As shown in Figure 2, the said shield may be formed from a leather piece 37 having a plastic or rubber overlay 38. Means is carried by the uppermost rack 6 and supports a shield 30. Specifically, the shield is provided with a transverse bore 39 and the uppermost rack is provided with a transverse bore at 40. Extending between the bores 39 and 40 is a tie rod 41 which has screw threaded ends for reception of nuts and washers for engagement with the top and bottom surfaces of the shield. Surrounding the rod 41 is a sleeve 42 which is passed through the bore 40 there being a coil spring 43 between the nuts at 44 and an end of the sleeve 42. Thus the tendency is for the spring 43 to constantly urge the shield to move toward the uppermost rack. The sleeve 42 may be held in a fixed position by members positioned on opposite sides of the uppermost rack, see Figure 5.

The form of bonnet or skirting shield illustrated in Figure 8 utilizes the same type of construction as shown for the open shield in Figures 1 and 2 with the exception that the skirting or the bonnet encircles the arcuate edge of the shield as shown at 47 with the said skirting provided with spaced slits 48 in nonalignment with the slots 11.

The operation, uses and advantages of the invention just described, are as follows:

As shown in Figure 1, the shield and upper end lower racks extend in sideways relationship to the limbs of the bow. Also the shaft receiving slots 11 are positioned outwardly from the side of the bow. Thus when the quiver is holding the arrows, the spacing is such that the arrows do not interfere with the hand which engages the hand grip 4. I provide for two types of arrows in the embodiment of the invention shown. As illustrated in Figure 2, a hunting arrow is shown at 50 and a target arrow at 51. Target arrows often differ in weight and type of arrowhead. In each instance, an arrow includes a head 52, feathers 53 and a nock portion which is adapted to engage the bow string 5. Assuming use of the arrow 50, the shaft thereof is passed through the restricted throat 12 and into the larger portion of the slot in the manner shown in Figure 3; in fact, this type of slot allows the arrow shaft to be rotated as it enters the slot and makes for easy entrance and exit thereof. The arrowhead 52 has its base portion engaging the top surface of the rack 6 as shown, while the pointed end will engage or penetrate slightly the leather portion 37 of the shield. This is sufficient to hold the arrow within the racks and against movement as the shield is resiliently urged by the spring 43 toward the uppermost rack at all times. The target arrow has its shaft passed through the openings 13 and is held by upward movement of the material of the racks as illustrated in Figure 2. This engagement is a frictional one but has been found to be sufficient with this type of arrow. Usually in target arrows the head is of tapered form with the base of the head substantially of the same diameter as that of the shaft. Consequently, this member may be pulled out of rack slots with ease.

That form of shield shown in Figures 1, 2, 6 and 7, I define as an open-shield as the semi-circular portion is open with the arrow heads protected by the small flanges

35 and 36 depending from the angular sides of the shield. These small flanges act as a stabilizing means for the said shield.

The second type of shield I have illustrated in Figure 8 and I have defined this type of shield as a bonnet or a skirting type. It will be observed that the slits 48 lie on opposite sides of the entrance slots 11 and that said slits do not extend the entire width of the said skirting or bonnet but terminate about midway of the width thereof. I have found in actual practice that a skirting or bonnet of two inches width may be slit inwardly from one inch from the bottom edge thereof. In this form of shield the skirting or bonnet encircles both the curved edge as well as the angular sides and therefore completely encircles the arrowheads. Preferably, the skirting or bonnet is formed from a flexible material such as a heavy cloth which may be reinforced at the top and bottom by plastic, or from other materials such as leather or from plastic alone. The encircling bonnet or skirting protects the hunting arrowheads from the top and at both sides of the shield. The bowman may draw the arrows from the racks without interference with the bonnet as is self evident. Replacement of the arrows is effected by pushing the arrowheads under the flaps formed between slits 48. This form of shield with its bonnet or skirting allows the bonnet or skirting to be decorated which adds to the appearance of the entire quiver. The circular form of rack with its arrow receiving slots permits the carrying of a large complement of arrows.

It will be observed that the two shields illustrated in Figures 6 and 8 have slide movement relative to the upper limb of the bow and that the slot 34 has greater transverse width than the thickness of the bow limb, as well illustrated in Figure 6. In fact, one edge bounding said slot is at an angle to horizontal so that the slot gradually increases in width inwardly of the shield. Such a construction allows the bow limb to flex without in any manner disturbing the position of the said shield upon the bow limb. Thus the bowman may flex the bow and the quiver with its shield will remain in the same position as it assumes when the bow is unflexed.

I claim:

1. A quiver adapted to be secured to the upper and lower limbs of a bow, including: an upper rack and a lower rack, each rack being of identical construction and of circular edge form; each rack provided along its circular edge with slots extending substantially radially inwardly of the rack for receiving the shafts of arrows, an elongated rod extending through said rack and having an end portion adjustably secured to the adjacent rack for spacedly maintaining the pair of racks in spaced apart relationship, means for securing each rack to a limb of the bow, a shield overlying the uppermost rack and spaced above the uppermost rack, means carried by the uppermost rack and slidably supporting said shield, and a spring operatively connected to said last mentioned means for urging the shield toward the uppermost rack.

2. The device of claim 1, the said shield provided with a slot extending inwardly thereof intermediate the flanged angular side edges and said slot being of greater width than the thickness of the leg of the bow.

3. An arrow quiver adapted to be spacedly secured to the upper and lower limbs of a bow, including: a pair of racks arranged in vertical spaced relation, each rack being of arcuate form and provided with a plurality of slots inwardly extending from the perimeter thereof, the slots of the upper rack being aligned with the slots of the lower rack, the aligned slots being adapted to receive the shafts of arrows, an elongated rod extending through said rack and having an end portion adjustably secured to the adjacent rack for spacedly maintaining the pair of racks in spaced apart relationship, a shield overlying and spaced above the uppermost rack, means carried by the uppermost rack and slidably supporting said shield, and a spring operatively connected to said

2,980,805

5

last mentioned means for urging the shield toward the uppermost rack.
